TABULATOR

William L. Collier, Chicago, Ill., assignor to
Remington Rand Inc., Buffalo, N. Y., a corpora-
tion of Delaware

Application February 19, 1941, Serial No. 379,601

7 Claims. (Cl. 197—177)

This invention relates to new and useful improvements in column selecting devices for machines such as typewriters, printing calculators, bookkeeping and accounting machines, and the like, in which it is desired to arrest a movable carriage in one or more selected columnar positions. Briefly and generally considered, the invention concerns a machine having a tabulator key adapted to operate a tabulator slide, a projectable stop on a tabulator rack corresponding to said slide, a stop operating member moved into operative position by the depression of the key, and means on the projectable stop to be engaged by said operating member during the movement of the rack to project the stop into operative position just before it reaches the position of its corresponding slide.

The object of the invention is to improve the operation of the tabulating mechanism of the machine whereby the speed and accuracy of the operation are enhanced.

Other objects and structural details of the invention will be apparent from the following description when taken in connection with the accompanying drawings, in which

Fig. 1 is a plan view of part of the apparatus;
Fig. 2 is a vertical cross section taken on the line 2—2 of Fig. 1;

Fig. 3 is an inverted plan view of a portion of the tabulator rack bar with several of the projectable stops thereon;

Fig. 4 is an enlarged plan view showing one of the projectable stops in engagement with its corresponding tabulator slide;

Fig. 5 is an elevation of the stop supporting plate;

Fig. 6 is an elevation of the projectable stop plate;

Fig. 7 is an elevation of the supporting plate and the projectable stop plate when assembled;

Fig. 8 is a semi-diagrammatic elevation of the connection between a tabulator key and the escapement rack lift-bar;

Fig. 9 is a front elevation of the stop operating member and cooperating parts;

Fig. 10 is a side elevation of part of the stop element; and

Fig. 11 is an end elevation of part of the stop element.

As shown in the drawings herein, a preferred form of the invention is illustrated in conjunction with a machine such as a Remington accounting machine in which there is provided a carriage frame 10 (Fig. 1) on which a platen 11 is supported in any suitable manner. The frame

10 is provided with brackets 12 at each end thereof, which support the usual tabulator rack bar 13. To the frame 10 is also pivoted an escapement rack bar 14 normally in engagement with the escapement pinion 15.

In the ordinary tabulating operation of machines such as the one illustrated, it is necessary to lift the escapement rack 14 from engagement with the pinion 15 in order that the carriage may be tabulated to the desired position. To lift this rack 14 there is provided a lift-plate or bar 16 (Figs. 1 and 2) disposed beneath the rack 14 and mounted on the end of a lift arm 17 fixed to a shaft 18 journaled in a bracket 19 fastened to the fixed frame 20 of the machine. To the other end of the shaft 18 is fixed an operating arm 21 to which is pivotally connected a dependent pull link 22.

The operation of this pull link 22 is well known in machines of the type shown. In the present embodiment, the machine is shown as having a power-operated tabulator mechanism although this form may be replaced by a manually operated tabulator mechanism. The form shown is similar to that shown and described in greater detail in Patent 2,064,154, issued December 15, 1936, to Dodge and Philbin, with particular reference to Figs. 2 and 21 thereof. Herein this construction is semi-diagrammatically shown in Fig. 8.

In Fig. 8 there is shown one of a series of manually operable tabulator keys 23 pivotally mounted to operate its push link 24. This link 24 will, in the manner clearly described in the Dodge et al. patent, supra, lift its corresponding interponent 25, and release the latch 26 to allow the cam 27 to actuate roller 28 and advance bail 29 which will engage and advance the lifted interponent 25. Each interponent 25 is connected to one of a plurality of pivoted arms 30 which is thereby advanced to engage and move rearwardly the slide plate 31 which, in turn, will rock its corresponding tabulator lever 32. It is, of course, understood that for each key 23 there is a corresponding lever 32.

At its upper end each lever 32 is connected to a corresponding tabulator slide plate 33 which is slidably disposed within the usual housing 34 (see Fig. 1), and is adapted to be projected therefrom in the usual manner as its respective key is operated.

Referring to Fig. 8 it will be seen that there is a bail plate 35 disposed in the rear of all the tabulator levers 32 and that to it is fixed an arm 36 connected to link 37, which, in turn, is con-

nected to one end of an arm 38, the other end of which is fixed on shaft 39. Another arm 40, fixed on shaft 39, is connected to the lower end of the previously mentioned pull link 22. It is obvious, therefore, that whenever any key 23 is operated, its corresponding tabulator lever 32 is oscillated and serves to rock ball 35. This movement is effective, by means of the linkage previously described, to lift plate 16. Thus, the carriage is released from the escapement pinion 15 to permit its movement.

One of the novel features of this invention comprises a stop operating member associated with the lift plate 16. As shown in Figs. 1, 2, and 4, this member comprises an arm 41, pivotally connected at one end to the bracket 18 and extending in a direction parallel to the rack bar 13. The free end of the arm 41 is provided with an upwardly extending cam element 42 which is disposed in front of the set of tabulator slides 33 (as in Fig. 1). Intermediate its ends the arm 41 is engaged by a lift spring 43 which extends rearwardly at right angles to the arm 41 and is anchored on a plate 44 (Fig. 1) which is fastened to the frame 20 adjacent to the bracket 19. The front end of this plate 44 is turned up as a flange 45 abutting the rear surface of arm 41. This flange 45 has a slot 46 therein (Fig. 9) which receives a pin 47 on the arm 41 so that the upward movement of the arm 41 is limited by this slot as the spring 43 tends to lift the arm. The arm 41 is provided with a lip 48 which projects under a portion of the arm 17. When the arm 17 is lowered, it presses on lip 48 which forces arm 41 downwardly against the lifting action of the spring 43. Therefore, when the arm 17 is raised by the action of the tabulator key 23, the downward pressure on lip 48 is removed and spring 43 is free to lift arm 41 to move the arm and the cam element 42 to what is designated as a stop-operating position. As stated before this position is determined by the limiting effect of the slot 46 on the pin 47 on arm 41.

The purpose of elevating the arm 41, as each tabulator key is depressed, is to place the cam element 42 thereon in an upward operating position to be in line with certain cooperating elements on each of a series of projectable tabulator stop members mounted on the rack bar 13. Since these stop members are substantially the same in construction, it will suffice to describe one in detail. They are shown particularly in Figs. 1, 3, 4, 5, 6, and 7. Each stop device comprises a supporting plate 49 (Fig. 5), and a projectable stop plate 50 (Fig. 6). These two plates are pivoted together at one end by engagement of a pin 51 with apertured lugs 52 on the plates, as shown. A spring 53 disposed between the plates tends to hold the projectable plate 50 in a retracted position, against the face of the tabulator rack 13, as shown in Fig. 3. The supporting plate 49 is provided with spaced dependent tooth-sectioned legs 54 which enable this plate to be clipped in any position over the rack bar 13, as shown in Figs. 2 and 3.

The projectable stop plate 50 (Fig. 6) has on its outer end a dependent stop finger 55. As shown in Figs. 1 and 3, when in normal retracted position, this finger 55 lies out of the path of any projected slide 33. The stop plate 50 also is provided with a supporting flange 57 having cam elements 58 thereon (see Figs. 6 and 7). These cam elements 58 depend from plate 51 and encounter cam element 42 on operating arm 41 when said arm 41 is raised to its operative po-

sition. The engagement of the cam elements 58 and 42 will project the stop plate 50 of the stop unit to the operative position shown in Figs. 4, 10, and 11. In this position, the finger 55 will lie against the back of the adjacent finger 54 of the supporting plate. The outer edge of finger 55 will extend beyond the outer edge of finger 54 and the inner edge of finger 55 will lie just inside of the top edge of finger 54 and thus be braced as it meets and is stopped by a tabulator slide 33.

According to Fig. 3 it will be noted that the cam elements 58 are spaced at different points on their supporting plates 56 so that their contact with the operating cam 42 will result in their projection at different predetermined times to engage predetermined tabulator slides 33. In Fig. 3 the variable settings of cams 58 on their supports are indicated by dot and dash lines, one of which is marked A and is drawn through the outer edge of the stop plate 50 in its retracted position. By reason of the variability of these settings the several stop plates 50 can be projected to engage with selected tabulator slides 33. These settings differ by an amount equal to the distance between consecutive tabulator slides 33 which is generally a tenth of an inch.

Viewing the machine from the front, it is assumed that the tabulator keys, the projectable stops, and the tabulator slides are numbered 1, 2, 3, 4, etc., from left to right. When key No. 1 is depressed the carriage is thereby released and cam 42 is raised to operative position. As stop No. 1 comes along, the cams 42 and 58 are so related as to project stop No. 1 just before it reaches the position of No. 1 slide 33. However, it is to be noted that the No. 1 stop is not projected until after it has passed the position of the No. 2 slide 33. This selectivity in the projection of the stops is achieved by reason of the variability of the positioning of cams 58 on their respective supports. Again, assume that key No. 6 is depressed. Then the carriage is tabulated, the arm 41 is lifted to position cam 42 and the stop plates 50 are successively projected as they pass the position of cam 42. It is evident, however, that stop plates 1, 2, 3, 4, and 5 are not projected until after they have passed the position of the slide 33 which is No. 6 in the series of slides. Therefore, as they pass the position of this slide, they are in retracted position and will freely pass by. However, the sixth stop plate has its cam so determined that it will be projected between the position of the sixth and the seventh slide so that it will be in position to engage with and be stopped by the sixth slide 33. This action takes place in a similar manner for each key. The stop plates may be as many in number as the number of tabulator keys 23 provided on the machine. It is also obvious that they may be placed in any position on the rack bar 13 except that they must be in order, namely, first No. 1 stop, then 2, then 3, etc. Also it is to be noted that since the first stop is arrested by slide No. 1, the next stop which is No. 2 must be placed one tooth further along the bar than the position at which it is to stop the carriage. For example, if the second stop is to arrest the carriage at 49 on the scale, it must be set at 41. Also, if the first stop were to be set at 10 and the next three at 10 points apart, the second would be set at 21, the third at 32, and the fourth at 43, since the first is arrested by the first slide, the second by the second slide, the third by the third

slide, etc., and these slides are each disposed successively to the right of the first slide which serves as an index point.

While I have described what I believe to be a highly desirable embodiment of my invention, it is obvious that many changes in form can be made without departing from the spirit of my invention, and, I, therefore, do not limit myself to the exact form herein shown and described, nor to anything less than the whole of my invention as hereinbefore set forth, and as herein-after claimed.

What I claim as new, and desire to secure by Letters Patent, is:

1. In a machine of the class described, a tabulator key, a tabulator slide movable by said key to an operative position, a movable tabulator rack, a projectable stop on said rack corresponding to said slide, a stop operating member movable by said key into an operative position, and means on the stop to be engaged by said member during the movement of the rack to project the stop, just before it reaches the slide position, into position to engage the slide.

2. In a machine of the class described having a plurality of tabulator keys, a plurality of tabulator slides selectively projected by said keys, a movable carriage and a tabulator rack movable with said carriage, the combination of a plurality of projectable stop elements on the rack corresponding to said slides, an operating element movable to an operative position upon the depression of any key, and means selectively positioned on each stop element to engage the operating element during the movement of the carriage to project each stop element, at a predetermined point in the travel of the stop element, into position to engage with and be arrested by its corresponding slide.

3. In a machine of the class described, a plurality of tabulator keys, a plurality of tabulator slides adapted to be individually moved to an operative position by the actuation of a corresponding key, a movable rack bar, a plurality of projectable stops on said bar corresponding to said slides, means selectively positioned on each stop, and means operated by any key and engaging the selectively positioned means on the stops in succession as the rack bar advances, the selective positioning of said means on the stop adapted to cause the projection of the stops only as each arrives at a position prior to that of its corresponding slide and subsequent to that of the next preceding slide.

4. In a machine of the class described, a tabulator slide, a depressible tabulator key connected thereto for operating said slide, a movable tabulator rack bar, a projectable stop on said rack bar, an operating cam device movable into an operative position by said key, and cam means on the stop to be engaged by said operating cam device during the movement of the rack bar, the cam means on the stop being selectively positioned so as to project said stop only when the stop reaches a position immediately prior to that of the slide.

5. In a machine of the class described, an escapement rack, a tabulator key, a rack lift bar engaging the rack and operated by the key to lift the rack, an arm, a stop operating cam on said arm, means on the lift bar engaging the arm to hold it in an inoperative position when the lift bar is in inoperative position, and a spring engaging the arm to lift it to an operative position when the restraining influence of the lift bar is removed.

6. In a machine of the class described having a movable tabulator rack bar, a stop element mounted on said bar which comprises a supporting plate provided with means to clip the plate on to the bar, a removable stop plate pivoted to the supporting plate, means cooperating with both plates to hold the stop plate in a retracted position, and a cam device on the stop plate to be engaged during the movement of the bar to project the stop plate to an operative position.

7. In a typewriting or like machine, a frame, a carriage movable relative thereto, a plurality of tabulator slides mounted on said frame in spaced relationship along the path of movement of said carriage, key operable means for selectively moving each of said tabulator slides to effective position, a plurality of stop elements corresponding to said tabulator slides, means for adjustably mounting each of said stop elements on said carriage for movement to and from effective position with relation to said tabulator slides, operating means on said stop elements disposed at different positions thereon corresponding to the spaced relationship of said tabulator slides, and means on said frame operable by said key operable means to a position coacting with said operating means to move each of said stop elements into effective position as it approaches the corresponding tabulator slide during the movement of the carriage.

WILLIAM L. COLLIER.
